UNITED STATES PATENT OFFICE.

ARTHUR J. BAZELEY, OF CLEVELAND, OHIO, ASSIGNOR TO NATIONAL MALLEABLE CASTINGS COMPANY, OF CLEVELAND, OHIO, A CORPORATION OF OHIO.

POCKET FOR ENGINE-COUPINGS.

1,358,696.

Specification of Letters Patent.

Patented Nov. 16, 1920.

Application filed May 8, 1919. Serial No. 295,544.

To all whom it may concern:

Be it known that I, ARTHUR J. BAZELEY, a citizen of the United States, residing at Cleveland, Cuyahoga county, Ohio, have invented new and useful Improvements in Pockets for Engine-Couplings, of which the following is a specification, reference being had to the accompanying drawings, in which—

- 10 Figure 1 is a side elevation of a coupler pocket embodying my invention; Fig. 2 is a front elevation thereof; Fig. 3 is a bottom plan thereof; Fig. 4 is a side elevation similar to Fig. 1 but showing the shim and shelf supporting the coupler head in elevating position; Fig. 5 is a detail showing the manner in which the shelf is applied to the pocket; Fig. 6 is a detail of the shelf; Fig. 7 is a side elevation of a modified form of my invention; Fig. 8 is a bottom plan thereof, and Fig. 9 is a detail of the shelf shown in Figs. 7 and 8.

My invention relates to pocket couplers for engines or tenders, which have an extended floor or shelf adapted to engage and support the coupler head forward of the mouth of the pocket, in order to prevent drooping or sagging of the coupler head when in service. My invention consists in providing a supporting shelf which is capable of reversal to provide vertical adjustment of the coupler heads and to compensate for wear. My invention also consists in the construction and arrangement of parts which I shall hereinafter describe and claim.

Referring to the drawings, A indicates the coupler pocket and B the coupler head. The pocket A is provided with the usual recess 2 for the reception of the coupler shank 3, the shank 3 and pocket A are apertured for the reception of a pivot pin 4, by which the coupler is secured in the pocket. The pocket A has a pair of forwardly extending arms 5 intended to support the extended floor or supporting shelf C. The supporting shelf C is a T-shaped piece, the head of which has an arcuate forward surface and consists in a pair of vertically extending and alternately used coupler supports 6 and 6' projecting, respectively, unequal distances from the horizontal plane of the studs 7 which extend laterally and engage the upper surfaces of the arms 5 of the pocket. The rearwardly extending leg or central

member 8 of the shelf C terminates in the 55 forwardly inclined projections 9. The pocket immediately below the recess 2 has a downwardly extending slotted lip 10, the inclined inner face of which is intended to engage a forwardly inclined face of a projection 9.

The shelf C is applied by placing the studs 7 upon the arms 5 and inserting a projection 9 beneath the lip 10 of the pocket, as is shown in Fig. 5. The shelf is then rotated 65 until the rearwardly extending leg 8 bears in the slot in the lip 10 and the forwardly inclined face of the projection 9 engages the inclined rear face of the lip 10. When the shelf is in this position it is prevented from 70 moving forward by the engagement of the projection 9 against the lip 10, and can not move sidewise because of its engagement in the slot in the lip and between the arms 5, nor rearwardly because its studs 7 abut 75 against the shoulders 11 of the arms 5.

The shim D is normally inserted between the top of the coupler shank 3 and the top of the recess 2 of the pocket A, and the shelf C is applied with the shorter coupler support 80 6 uppermost, as is shown in Fig. 1. When, however, it is desired to raise the coupler head, either because of wear of the pocket parts or because of settling of the locomotive springs, the shim D is inserted in the bottom 85 of the recess 2 beneath the coupler shank 3 and the shelf C is inverted, as is shown in Fig. 4, thereby causing the longer support 6' of the shelf C to engage the under side of the coupler head at a distance commensurate to 90 the elevation of the coupler and shank caused by the insertion of the shim D.

In Figs. 7, 8 and 9 I have shown a modification of my invention, in which the rearward extension of the shelf C' consists in a 95 short lug 12, which engages a projection 13 on the lower lip of the pocket and which is fastened to such projection by a bolt 14. Recesses 15 are provided in the arcuate-shaped portion of the shelf so as to straddle 100 the arms 16 and thereby provide a more effective interlock between these parts.

The terms and expressions which I have employed are used as terms of description and not of limitation and I have no intention in the use of such terms and expressions of excluding any mechanical equivalents for the features shown and described, or por-

tions thereof, but recognize that various structural modifications are possible within the scope of the invention claimed.

What I claim is:

- 5 1. In a coupler pocket, a coupler head pivotally secured in said pocket, forward extensions from the under side of said pocket, a reversible shelf seated on said forward extensions and having a rearwardly extending portion engaging a portion of said coupler pocket to prevent removal in a forward direction.
- 10 2. In a coupler pocket, a coupler head pivotally secured in said pocket, forward extensions from the under side of said pocket, a reversible shelf having laterally extending members engaging the said forward extensions, vertically extending coupler supports on said shelf extending unequal distances from the horizontal plane of said members, and a rearwardly extending member engaging a forward portion of the pocket.
- 15 3. In a coupler pocket, a coupler head pivotally secured in said pocket, a shelf for supporting the coupler head, the pocket having forwardly extending arms supporting said shelf and holding it against lateral movement, the shelf having a rearwardly extending central portion engaging the under side of the coupler pocket and being held by such engagement from displacement in a forward direction.
- 20 4. In a coupler pocket, a coupler head pivotally secured to the pocket, forward extensions from the under side of said pocket, a shelf supported on said forward extensions, said shelf engaging the under side of the coupler head and maintaining it substantially in a horizontal plane, and means on said extensions to prevent rearward and lateral movement of said shelf, said shelf also having a rearward extension engaging the coupler pocket to prevent forward movement of said shelf.

ARTHUR J. BAZELEY.
